COIL AND BUFFER SPRING SYSTEM FOR A GUN MOUNT

Edward H. Cabaniss, Newton C. Garland, and Albert L. Hardy, Schenectady, Joseph B. Gibbons, West Albany, and Leon Webster Frayer, Schenectady, N. Y., assignors to the United States of America as represented by the Secretary of the Air Force

Application May 25, 1953, Serial No. 357,212

1. Claim. (Cl. 89—44)

This invention relates to a gun mount and in particular to a dynamic automatic gun mount for aircraft.

An object of this invention is to provide a method of reducing the vibratory forces transmitted from the gun to the support of an automatic gun.

A further object of this invention is to provide a gun mount capable of reducing the recoil forces by using a spring and buffer system so arranged and dimensioned that the buffer absorbs a portion of the recoil energy with the result that the firing of the second and each succeeding shot occurs while the gun is moving forward. This causes the gun to reverse its direction and start in the recoil direction with one-half the velocity of a free recoil.

A still further object of this invention is to provide a dynamic automatic gun mount provided with a movable support adapted to carry a gun in a recoil and counter-recoil direction, and with the movable support and the gun being constrained for movement on a relatively stationary support. Coil springs are mounted between the movable support and stationary support and are adapted to cooperate with a buffer spring which is fixed to the stationary support and which is adapted to be actuated by the movable support. The movable support is driven in a recoil direction by the impulse from the firing of the gun. The buffer spring assembly absorbs and stores that portion of the energy which was not stored by the coil springs so that the buffer spring and coil spring cooperate to drive the movable support in a counterrecoil direction at a frequency so as to be moving in a counterrecoil direction when the next recoil begins.

These and other objects will become more apparent when read in the light of the accompanying drawings and specification, which specification and drawings are not necessarily intended to limit the scope of the invention but is intended merely as an embodiment of the invention, but for such scope reference shall be made to the appended claim, wherein:

Fig. 1 is a plan view showing the arrangement of the springs on the stationary support with respect to the movable support.

Fig. 2 is a cross-sectional view taken on lines 2—2 of Fig. 1.

Fig. 3 is a right elevation side view of Fig. 1.

Fig. 4 is a cross-sectional view taken on lines 4—4 of Fig. 1.

In the following description and in the claim parts will be identified by specific names for convenience, but they are intended to be as generic in their application to similar parts as the art will permit.

Referring to the drawings, the numeral 10 generally designates a gun mounted on a yoke 12. Another portion of the gun is slidably mounted and constrained in a recoil and counterrecoil direction but is not shown since this forms no part of the invention. The yoke 12 is pivotally mounted on a support 14 on bolts or pins 18. The support 14 is bolted to longitudinal shafts 16. The shafts 16 are provided with reduced end portions 17 and 19 and an intermediate built-up portion 21. The built-

2

up portion 21 is provided at its ends with threaded portions so as to receive stop nuts 22. Vertical supports 24 are securely fastened to a base 25, the supports being provided with bearings 26 adapted to be received in openings 27. Intermediate the vertical supports 24 are provided abutments 28. Slidably mounted on the shaft portion 21 is a pair of bushings 30 which are adapted to contact either the nut 22 or the abutment 28. Soft springs 32 are mounted about the shafts 16 and between the slidable bushings 30. A longitudinal buffer shaft 34 is also mounted between the shafts 16 and is fixed to the support 14. The other end of the shaft 34 is slidably mounted in a buffer assembly housing 36, the buffer assembly base 38 being fixed to the base 25 by bolts or the like. A nut 39 is threadably mounted on shaft 34. The buffer assembly housing 36 is provided with plungers 40 and 41 slidably mounted on the shaft 34 and are constrained on the shaft by the friction ring springs 42. The buffer sleeve 44 is mounted on the buffer shaft 34 so that it is adapted to engage the plunger 40. The factors determining the frequency of vibration of the system is made possible by the dimension C and the springs 42 and 32 so as to have a particular frequency with respect to the firing rate of the gun.

25 In operation, when the gun is fired the impulse from the recoil moves the gun in a rearward direction, a portion of the energy being absorbed and stored by the friction ring spring 42, after the springs 32 have stored a portion of the energy. This is because the friction spring 42 will not come into play until the buffer sleeve 44 on the shaft 34 engages the plunger 40. The friction springs 42 and the coil springs 32 are constrained so that the friction springs absorb a portion of the energy of the free recoil and then the springs 32 and 42 drive the gun in the counterrecoil direction. Due to the frequencies of springs 32 and 42 the gun is moving forward when the impulse from the next round is transferred to the movable support 12 and 14. In other words the buffer and spring systems have such a natural frequency with respect to the firing rate of the gun so as to have the gun moving in a counterrecoil direction when the next recoil is begun. A portion of the free recoil energy has been removed from the system by the buffer spring and the gun will move in the counterrecoil direction with approximately one-half a free recoil velocity when the second round is fired. This phenomena is the result of the spring system having a predetermined frequency and absorbing a predetermined amount of the energy. The firing of the second round causes the gun to reverse its direction and start to move in the recoil direction with approximately one-half the velocity of a free recoil. Thus approximately one-fourth the energy of the free recoil need only be stored by the recoil spring for the second and each succeeding shot of the gun. This is true because the velocity of the free recoil simply stated is:

$$V_G = \frac{V_P M_P}{M_G}$$

60 in which V_G =free recoil velocity of the gun, V_P =velocity of the projectile, M_P =mass of the projectile, and M_G =mass of the gun. This velocity (V_G) of the free recoil is approximately the theoretical velocity change of the gun due to firing. If the gun is moving forward with a velocity of $V_G/2$ at the time the firing impulse is transferred to the sliding or moving support, the recoil velocity will be $V_G/2$. The velocity change will be $V_G/2$ since the counterrecoil velocity is $V_G/2$ and will subtract from the V_G , which is the free recoil velocity of the gun, thereby resulting in a recoil velocity of $V_G/2$. Since the kinetic energy of the free recoil is $\frac{1}{2}M_G \cdot V_G^2$ in which V_G is actually $V_G/2$, the kinetic energy of the recoil of this

system which need be stored would be $\frac{1}{2}Mg(Vg/2)^2$ which is equal to $\frac{1}{2}(\frac{1}{4})MgVg^2$.

Once the system stabilizes it is not necessary for the buffer system to remove energy since the coil springs are selected to provide the desired counterrecoil velocity. This stabilized condition exists generally after the first few rounds are fired. The buffer serves to restabilize the system if the stabilization condition is lost during the continuous firing of the gun.

By this arrangement of parts a large reduction of the vibratory forces transmitted from the gun to the base is realized. This is the result of the low spring gradient in the recoil springs and that the storage of approximately only one-fourth of the free recoil energy in the recoil system will be required on the majority of shots.

It is apparent, the specific embodiment shown above has been given by way of illustration and not by way of limitation and that the structures above described are subject to wide variation and modification without departing from the scope or intent of the invention, all of which variations and modifications are to be included within the scope of the present invention.

What is claimed is:

An apparatus for reducing the vibratory forces transmitted from a gun to its base comprising a base, supports extending upwardly from said base, a pair of shafts, said supports having openings therein to receive said pair of shafts, abutments extending upwardly from the base intermediate the supports, a pair of slidable bushings mounted on each of said shafts for engagement with said abutments,

each end of said pair of shafts having a threaded portion, nuts threaded on said threaded portions for engaging the slidable bushings, coil springs mounted between each of the pairs of slidable bushings and normally biasing them into engagement with said abutments, movable gun supporting means mounted on said pair of shafts, a gun disposed on said gun supporting means, a buffer shaft having one end fixed to the gun supporting means, a buffer housing fixedly mounted on the base, said buffer shaft being slidably mounted in the buffer housing, a buffer sleeve mounted on the buffer shaft a predetermined distance from said buffer housing, and a buffer spring mounted around said buffer shaft within said buffer housing to form a coil and buffer spring system with the coil springs, said movable support means being driven in a recoil direction by firing of said gun to actuate said coil springs and said buffer spring whereby said coil and buffer spring system reduces the vibratory forces transmitted to said base from said gun through said gun supporting means.
